UNITED STATES PATENT OFFICE.

DAVID J. NEWMAN, OF BUFFALO, NEW YORK.

COMBINATION-LOCK.

1,357,720.

Specification of Letters Patent.

Patented Nov. 2, 1920.

Application filed May 29, 1917. Serial No. 171,778.

To all whom it may concern:

Be it known that I, DAVID J. NEWMAN, a citizen of the United States, residing at Buffalo, in the county of Erie and State of New York, have invented new and useful 5 Improvements in Combination-Locks, of which the following is a specification.

This invention relates to a combination lock adapted for use on the doors of freight cars and the like, and is an improvement in 10 the device shown in Letters Patent of the United States No. 1,136,357, granted to me April 20, 1915.

Its object is the provision of a simple, 15 strong and reliable lock of this character which can be manufactured at a reasonable cost.

In the accompanying drawings: Figure 1 is a fragmentary side view of a freight car equipped with my improved lock. Fig. 2 is 20 an enlarged fragmentary vertical section of the same, lengthwise of the freight car. Fig. 3 is a transverse vertical section on line 3—3, Fig. 2. Figs. 4 and 5 are horizontal sections on the correspondingly numbered 25 lines in Fig. 2. Fig. 6 is a fragmentary, perspective view of the locking bolt. Fig. 7 is a top plan of one of the tumblers.

Similar characters of reference indicate 30 corresponding parts throughout the several views.

1 indicates the casing of the lock which is preferably rectangular in form and secured in a vertical position to the car body. 35 2. In the construction shown, the face of the car body adjacent the door opening is provided with a recess 3 in which this casing is arranged and in which it is secured by bolts 4 applied from the inside of the car 40 so as to be concealed from view and inaccessible to car burglars. A locking eye or lug 5 is preferably movably fastened to the front edge of the car door 6, by means of a staple 7 passing through a slot or elongated opening 8 in the adjacent rear portion of said eye. As shown in the drawings, 45 the rear end of this eye is arranged between the inner and outer walls of the car door, while its front end extends beyond the edge 50 of the door and passes through an opening 1^a in the side of the lock casing.

9 indicates a locking pin or bolt passing vertically and upwardly into a cylindrical bore or chamber 10 of the lock casing, the 55 opening 11 of the locking eye 5 and through

a series of circular tumblers or washers 12. These tumblers are arranged one above another in the casing 1 and fill the space between the upper side of the eye 5 and the upper end of said chamber. The uppermost tumbler bears with its upper side against an inwardly-extending shoulder 13 formed in the upper part of said chamber, while the lowermost tumbler is provided in its bore with a tapering seat 14 adapted to rest on a correspondingly-shaped shoulder 15 formed at the lower end of the locking bolt. These tumblers are closely fitted in the opening of the casing 1 so that they are centered by it. By this construction, the tumblers are positively held against displacement vertically of the case, in the closed position of the door, and yet are free to rotate therein when it is desired to work the combination for unlocking the door. 75

In the preferred construction shown in the drawings, the tumblers are provided in diametrically-opposite sides of their bores with notches 16 extending entirely through them and adapted to receive two rows of teeth 80 or projections 17 arranged on diametrically opposite sides of the locking bolt 9. These teeth are abrupt on their undersides and inclined on their upper sides, while the lateral edges or corners of their inclined and abrupt faces are chamfered, as shown at 17^a and 17^b. The edges of the notches in the tumblers are likewise preferably chamfered. This construction facilitates the turning of 85 the tumblers in the act of unlocking the bolt 90 and avoids binding or catching of the bolt-teeth on the tumblers. These chamfered edges also serve to accurately align the tumbler notches in inserting the bolt, in case they should be slightly out of line. 95

In its underside each tumbler is provided with a beveled recess 18 which receives the corresponding upper side of the contiguous pair of bolt teeth. On its face, each tumbler has an annular row of suitable combination-indications, such as letters or numerals which are exposed one at a time through a vertical sight opening 20 in the front side of the lock casing. To facilitate the turning of the tumblers, vertical grooves or depressions 21 may be provided at suitable intervals in their faces. 100

The locking bolt 9 is provided below the tapering shoulder 15 with a neck portion 22 preferably of cylindrical form, which en- 110

gages the eye 5 and thereby locks the door. Below this neck portion, the bolt is provided with a head or enlargement 23 between which and the lowermost tumbler the eye is confined when in its locked position. At its lower rear side, the locking bolt may be provided with a key or feather 24 arranged to engage a keyway 25 in the casing for the purpose of preventing the bolt from turning 10 in the casing.

To facilitate the withdrawal of the bolt in unlocking the door, the underside of the bolt-head 23 may be provided with finger notches or recesses 26.

15 The front side of the casing 1 is preferably provided with a shield or cover plate 27 whose side edges are bent inwardly to form lips or guide flanges 28 which are adapted to engage corresponding grooves 29 formed in the sides of the casing and extending the full length thereof. The upper edge of this shield is also bent inwardly to form a stop lift or flange 30 which is adapted to engage a groove 31 in the upper side of the lock casing and thereby limit the downward movement of said shield. A suitable finger piece 32 may be provided for sliding the shield up and down when necessary. By thus covering the exposed front 30 side of the lock in the manner described, the same is weather proof and rusting or corroding of the parts is prevented.

Immediately below the lock casing, the face of the car body 2 is recessed, as shown 35 at 33, for a distance sufficient to permit the reception of the bolt and tumblers when the same are removed for releasing the locking eye 5 preparatory to opening the door.

40 By arranging the locking bolt and tumblers vertically or at right angles to the locking eye, any strains due to the horizontal vibration of the car, are exerted crosswise of the bolt at and adjacent to its neck 22, avoiding stripping of its teeth and rendering the lock stronger and more durable and reliable.

Certain of the letters or indications on the faces of the tumblers are arranged in 50 line with their locking notches, so that when the several tumblers are turned to expose those particular letters through the sight opening in the lock casing, the notches of the several tumblers will register with the teeth of the locking bolt, allowing the latter to drop out of the tumblers and into the recess 33 of the car body and unlocking the latter. As soon as the door is opened and the locking eye withdrawn from the 55 casing, the tumblers drop by gravity on to the locking bolt and remain there until it is desired to again lock the door. To lock the door, the tumblers, while still in this registering position are removed from the

bolt and inserted in the bore of the casing, 65 after which the door is closed tightly against the door jamb and the locking bolt passed through the eye and the registered notches of the several tumblers. The latter are then rotated to cause their notches to 70 break register with the teeth of the bolt.

The combination of the lock can be readily changed by transposing the tumblers or changing their order, each tumbler bearing a row of letters or characters differing in sequence or arrangement from those of the other tumblers, to afford a large variety of combinations. Furthermore, such changes can be easily made by hand and without the use of tools. 80

The improved combination lock, it will be noted, is comparatively simple and possesses great strength. The locking elements are all inclosed and hidden from view, thereby making it almost impossible for a 85 burglar or other unauthorized person to gain access thereto.

By pivotally mounting the eye-member 5 on the door, the eye is free to enter the lateral opening of the casing notwithstanding settling or any other imperfections of the door.

By countersinking the lock-case in a recess of the car body, as shown; the lock is substantially flush with the face of the body 95 and not liable to catch on objects and be injured or broken off.

I claim as my invention:

1. A combination lock, comprising a casing adapted to be attached to a door-frame 100 and provided in its side with an opening, a series of tumblers arranged in said casing, an eye adapted to be attached to a door transversely to the axis of said tumblers and to pass through said opening, and a 105 locking member passing through said eye and interlocking with said tumblers.

2. A combination lock comprising a casing closed at one end and open at its opposite end and provided in its side with an 110 opening, rotary tumblers arranged in the casing between its closed end and said opening, an eye arranged substantially at right angles to said casing and adapted to enter said opening, and a locking bolt passing 115 through said eye and said tumblers and having means adapted to interlock with the tumblers.

3. A combination lock comprising an upright casing having a sight opening, a vertical series of rotatable tumblers arranged in said casing and exposed through said opening, said tumblers having central openings provided with locking notches, the casing having a lateral opening below the 120 lowermost tumbler, an eye arranged to enter said lateral opening, and a toothed vertical locking bolt constructed to pass through 125

said eye and tumblers and provided with a shoulder for supporting the lowermost tumbler.

4. The combination with a door carrying a horizontal eye, of a door-frame provided in its face with an upright recess, a casing secured to the face of the frame above said recess, said casing being closed at its upper

end, opening at its lower end into said recess and provided with a lateral opening for 10 receiving said eye, a vertical series of rotary tumblers arranged in the casing, and a locking bolt passing upwardly through said eye and the tumblers and interlocking with the latter.

DAVID J. NEWMAN.
